UNITED STATES PATENT OFFICE.

ARNOLD MOETTELLI, OF OBER WINTERTHUR, SWITZERLAND.

APPARATUS FOR CASTING AND COOLING MOLDINGS.

Application filed May 1, 1922. Serial No. 557,637.

To all whom it may concern:

Be it known that I, ARNOLD MOETTELLI, a citizen of Switzerland, residing at and whose post-office address is Ober Winterthur, Römerstrasse 21, Switzerland, have invented certain new and useful Improvements in Apparatus for Casting and Cooling Moldings, for which I have filed application in Germany May 8, 1918, Czechoslovakia March 13, 1922, Sweden March 18, 1922, England March 23, 1922, Belgium March 26, 1922, France March 29, 1922, of which the following is a specification.

It has already been endeavoured in different ways to utilize the heat available in forming and cooling hot substances, as for instance blast furnace slags, pigs and the like, for technical purposes, for instance, for the generation of steam. 15
In those instances the moulds are conveyed through a space below the boiler, into which space a continuous current of fresh air enters at a point near the entering port for the moulds, which will absorb heat 20
from said moulds and transfer such heat to the bottom of the boiler and the walls of the boiler-tubes. The force of the current of air and the heating of the boiler can be controlled by means of a slide arranged in 25
front of the chimney.

Thus only a flow of air took place, which after heating practically went to waste, and loss of heat was caused on the one part, while on the other side the castings were 30
cooled down too fast in consequence of the continuous admission of fresh cool air. But especially lump-slag must be cooled slowly, otherwise it will crumble and tear up or become useless by decomposition. Moreover, 35
through the continuous admission of fresh air oxidation was experienced for instance in the case of cast pig.

In order to avoid these drawbacks the present invention provides for the castings 40
consisting of molten slag or red-hot metal and so on to be closed up in a chamber, in which a gaseous agent is circulated by means of a blower or other suitable device. The 45
gaseous agent thus is not only employed for a single passage through said chamber, but the same particles of the said agent are again and again utilized for cooling and heating through the continuous circulation, while neither fresh air is admitted to nor 50
gaseous agent drawn from the chamber.

Circulation can be effected by means of a blower, capable of being regulated, so that the speed of circulation may be adapted to the requirements of the steam generator or the varying number of castings fed. 60

In the drawing a mode of construction of the device for carrying the subject matter of the present invention into practice is illustrated, in which

Fig. 1 is a vertical cross-section through the device; and

Fig. 2 a section taken on line II—II of Fig. 1.

The hot liquid mass carried by means of a ladle-car *a* from the furnace is conveyed 70 by means of a distributing arrangement *b* to the tilting-moulds *c* carried by an endless chain device of well known construction, and the said moulds are conducted by means of a driving device not shown in the direction of the arrows through heating flues *d*, and which moulds are tilted by means of a tilting device which is also not shown or described when leaving the lower boiler tubes. While passing through the boiler the 75 hot mass will transfer owing to radiation and conduction so much heat to the boiler, that it grows stiff and leaves the moulds after tilting in the shape of solid red-hot pigs dropping into an inclined chute *f*, from whence said pigs will pass into the cups 80 of an elevator, conveying them to a storing receptacle *h*. Here the cast pigs will remain until cooled down and after that they are transported by means of the belt-conveyor *i* over the chute *h* into carriages below said chute. The circulation of the gas 85 is as follows. From the blower *l* the gases pass through a conduit to the bottom of the chamber *h*, and up through the spaces between the stored pigs in the chamber. The 90 gases then pass through a conduit to the elevator shaft and down the same to and through the flues *d* of the boiler *e*. The gases then pass upwardly to the rear of the 95 boiler *e*, and through the tubes thereof to the front of the chamber in which the boiler is arranged where the gases then pass around the boiler to the rear of the chamber, and through an opening at the rear between the said chamber and the chamber in which the boiler *e* is arranged. From the 100 chamber in which the boiler *e* is arranged, the gases pass by way of a conduit to the blower. Thus the air is circulated through 105 110

2
 an endless closed conduit including the storage receptacle h , shaft for the conveyor g , flues d of the lower boiler, fire tubes of the upper boiler and the ducts leading to and from the fan. Through suitable closing devices of usual construction, and not shown all spaces can be shut air-tight. If the blower is started and the spaces are all closed the neutral gases contained in said spaces and formed from the air originally present, are forced through the boiler in the direction of the arrows and pass over the goods to be cooled, whereby they will absorb heat from the latter and cool them, and the gases will again transfer their heat to the boiler and cool down again. In this manner it is possible to transfer the heat of the goods to be cooled to the boiler in an economic manner. The pigs bottommost in the storing receptacle are cooled first, so that said receptacle will always deliver the pigs cooled most. The blower is equipped with a controlling slide or trap and with a device for regulating the number of revolutions, in order to regulate the amount of heat transferred to the boiler by accelerating or decreasing the speed of circulation of the heat-bearing agent in such a manner, that the generation of steam can be regu-

lated as desired. The storing receptacle h is of such dimensions, so that it acts as a heat-accumulator.

It will be evident that the mechanism shown at e and e constitutes a heat exchanger, the heat from the heated air being taken up by the water, the air being cooled, and being returned to be again heated.

I claim:

In an apparatus of the character specified, the combination with a closed conduit which includes a heat-exchanger and a storage receptacle, means for conducting highly heated material through the heat-exchanger, means for conveying the material from the heat-exchanger to the place of storage through the closed conduit, and means for continuously circulating a heat-transferring medium within the closed conduit, first through the storage receptacle and then over and past the highly heated material, through the heat-exchanger and back to the storage receptacle.

In testimony whereof I have affixed my signature in presence of two witnesses.

ARNOLD MOETTELI.
